UNITED STATES PATENT OFFICE.

NATHAN S. CONOVER AND LLOYD V. S. CONOVER, OF CLINTON, NEW JERSEY.

INCUBATOR.

SPECIFICATION forming part of Letters Patent No. 716,670, dated December 23, 1902.

Application filed March 2, 1901. Serial No. 49,653. (No model.)

To all whom it may concern:

Be it known that we, NATHAN S. CONOVER and LLOYD V. S. CONOVER, citizens of the United States, residing at Clinton, in the county of Hunterdon and State of New Jersey, have invented new and useful Improvements in Incubators, of which the following is a specification.

Our invention is an improvement on those incubators in which a hot-air drum and flue are used in addition to the heating-pipe through which the products of combustion arising from the heater are passed for the purpose of heating the incubator.

15 The primary object of this invention is to provide a device of the character described in which a uniform degree of heat will be maintained at all times during the process of hatching the eggs, and a further object is to 20 provide means whereby the products of combustion from the heating agent will be carried off and prevented from coming in contact therewith.

25 Further objects as well as the peculiar construction of this invention will be clearly described in the following description, recited in the claim, and illustrated in the accompanying drawings, in which—

30 Figure 1 is a vertical longitudinal central sectional view of an incubator constructed in accordance with our invention. Fig. 2 is a cross-section. Fig. 3 is a horizontal section on the line 3 3 of Fig. 1. Fig. 4 is an enlarged detail view of the incubator-heater chambers. 35 Fig. 5 is a top plan view of the damper mechanism. Fig. 6 is a side elevation of the thermostat, and Fig. 7 is a detail view of the end door for permitting the escape of superfluous heat and also to permit a draft in the device.

40 Referring now to the drawings by numerals of reference, 1 designates a rectangular casing having a hollow top, bottom, back, and ends and positioned on suitable standards or legs 2. The top and bottom of this casing are 45 provided with non-conducting packings of asbestos and designated by the reference-numerals 3 and 4. Similar non-conducting packings 5 and 6 are also provided in the ends and are inclosed by suitable partitions.

50 Positioned in the bottom of the casing and

near one end thereof is the heating device, which consists of an inverted hollow frustum of a cone, providing a main combustion-chamber 7, in which the products of combustion are permitted to rise and diverge as they 55 ascend from a lamp (not shown) connected with the lower end thereof. From this combustion-chamber projects at the outer side of the top thereof an outlet pipe or chimney 8, extending through the top of the casing. An 60 inverted hollow frustum of a cone provides an auxiliary combustion-chamber 9, in which some of the products of combustion are permitted to rise. This auxiliary combustion-chamber is formed integral with the cone 7 65 and inclosed by a hot-air drum 10, which extends upwardly to a point slightly above the center of the casing and has a transverse throat or discharge end 11 at its upper extremity. A metallic wall 12 surrounds the 70 heating device above described. Within this wall we pack non-conducting material 13, preferably asbestos. An elbow-pipe 14, having a downwardly-extending limb or joint 15, communicates with the drum 10 and is de- 75 signed for the admission of air into the drum from beneath the bottom of the incubator. A horizontally-arranged longitudinal outlet-pipe 17 is positioned in the top of the incubator and communicates with the chimney 8 80 at one end. Near the opposite end of said pipe we arrange an enlarged transverse box or casing 18 for the reception of the products of combustion which pass through said pipe 17. In line with the pipe 17 is a short pipe 19, in 85 which is sleeved a perforated cap 16, whereby the draft in the pipe 17 can be regulated.

85 A metallic hot-air conduit (designated by the reference-numeral 20) is positioned immediately below the pipe 17 and extends 90 nearly the entire length of the casing 1. This conduit is connected at its lower edges to a board, so as to form a rectangular heating-flue communicating with a transverse box-like chamber 21, having an open bottom to 95 permit the heat to pass down into the body of the incubator and through the eggs positioned on the egg-containing screen 22. The bottom of the transverse box-like chamber 21 is provided with a double layer of felt, (desig- 1cc

nated by the numerals 23 and 24,) the lower one extending to a distance slightly in excess of the middle of the casing and is secured to a longitudinal box-like chamber 21^a, depending from horizontal partitions 21^b, and to a vertical partition 25 by a suitable batten 26. This partition 25 has a double wall, between which is a packing of asbestos 27. The heat which passes off from the pipe 17 accumulates in the upper part of the casing and passes down through the slots 28 and 29, between the horizontal partitions 21^b and the longitudinal conduit 20, through the chamber 21^a, and is filtered through the felt layer 23. A cloth partition 30 is arranged beneath the egg-carrying screen and in a measure retards the progress of the heat, so as to confine the air at a given temperature in the hatching-chamber provided by means of the 10 felt partition 25 and the cloth partition just referred to. However, the draft caused by opening the door 31 in the end of the casing will cause excess of heat to pass through said cloth partition 30 and thence through an 15 opening 32 in the partition 25, thence around an air-chamber 33, surrounding the casing 12, through an opening 32^a into the hollow end, and thence into the ends of and out through the opening 34, which can be closed 20 or opened by the double door 31.

On one side of the casing and confined within the hatching-chamber 35 we arrange a thermostat 36, comprising an intermediate strip, to each side of which is bolted or riveted diaphragm-strips 37 and 38. Projecting upwardly from these strips and secured in suitable perforations is a threaded rod 39, which extends through the top of the casing and carries at each end threaded taps 40 and 41, respectively. The tap 40 on the bottom end of the rod is designed for the purpose of adjusting the thermostat so as to actuate the rod at a predetermined temperature. The tap 41 is provided for the purpose of affording an adjusting device for the pivoted damper-lever 42, working on suitable journal-bearings 43 on the standard 44. On the rear end of this lever we provide an adjusting compensating weight 45, while on the other 50 end is positioned a disk damper 46, adapted to fit over the tube or chamber 8.

The outlet-pipes 47 and 48 in the corners of the casing communicate with the chamber 18 and are for the purpose of carrying off an 55 excess of heat as well as the products of combustion which might pass through the pipe 17.

In actual practice a lamp or other heating medium will be placed directly under the bottom of the combustion-chamber 7, and the chimney thereof will extend up within said combustion-chamber. The smoke and other products of combustion will pass up through the pipe or chimney 8 until the pipe 17 is 60 reached. The current of air caused by the outlet-pipes 47 and 48 will direct the products

through said pipe 17 and into the chamber 18. By reason of the fact that the pipe 17 is positioned in the center longitudinal of the casing the heat will be equally distributed on both sides thereof, and part of the heat will pass down through the slots 28 and 29 into the hatching-chamber 35 after passing through the felt layers or partitions 23 and 24. The heat generated in the drum 10 will also pass 70 into the rectangular pipe positioned immediately below the pipe 17 and will also distribute the heat equally on both sides of the casing. The heated air will pass down through the egg-containing screen and after 75 passing through the partition 30 will pass off into the outer air, as explained hereinbefore. If, however, the excess of heat occurs within the incubator, such as would endanger the successful hatching of the eggs, the thermostat 36 will be expanded, so as to actuate the rod 39, and thereby cause the disk damper 46 to be unseated from the top of the chimney 8, and thereby permit the products to 80 pass into the open air without permitting the same to enter the pipes hereinbefore referred to. As soon as the normal temperature is obtained within the incubator the thermostat will contract and again permit the disk 46 to be seated, and the heat will be conducted 85 through the proper channels until such time as an excess occurs, when the superfluous amount will be again exhausted.

While we have specifically described in detail what to us at this time appears to be the 100 very best means of accomplishing the desired result, we would have it understood that slight changes or alterations might be made in minor details of construction and without departing from the spirit or sacrificing any 105 of the advantages of this device. For instance, for convenience in assembling the parts we arrange the thermostat to one side of the casing; but it is obvious that this thermostat might be positioned at any point intermediate the sides and still be effective. Other changes might also be made without departing from the spirit of our invention, and we therefore do not confine ourselves 110 strictly to the exact construction shown. 115

What we claim, and desire to secure by Letters Patent, is—

The combination with an incubator comprising communicating hatching and heating chambers, of a heating device having a main chamber with which a lamp may be connected, a vertical pipe connected with the main chamber, an auxiliary chamber surmounting the top of the main chamber, a longitudinal outlet-pipe extending from said vertical pipe 120 over the hatching-chamber, a transverse box located over the hatching-chamber at the end opposite to the heating device and having outlets at the corners with which the outlet-pipe communicates, a hot-air drum 125 surrounding the auxiliary chamber, a fresh-air pipe connected to the said drum, a longi- 130

tudinal hot-air pipe extending from the drum, a longitudinal conduit extending from a point over the hatching-chamber and having a bottom-opening with which the said longitudinal hot-air pipe communicates, and a transverse chamber located beneath the opening of the hot-air conduit and having a filter-cloth.

In testimony whereof we affix our signatures in presence of two witnesses.
